UNITED STATES PATENT OFFICE

HANS SCHWEIZER, OF NEW YORK, N. Y., ASSIGNOR TO THEO. TIEDEMANN & SONS, INC.,
OF NEW YORK, N. Y., A CORPORATION OF NEW YORK

DESIGN FOR A TEXTILE FABRIC

Application filed May 22, 1929. Serial No. 31,332. Term of patent 7 years.

To all whom it may concern:

Be it known that I, HANS SCHWEIZER, a citizen of the Republic of Switzerland, and a resident of the city, county, and State of New York, have invented a new, original, and ornamental Design for Textile Fabrics, of which the following is a specification, reference being had to the accompanying drawing, forming a part hereof, in which the figure shown is a plan view of a section of fabric, showing my new design.

That portion of the drawing confined within the space enclosed by the dotted lines A and B comprises one complete design unit, the same being repeated for the length and width of the fabric piece.

I claim:

The ornamental design for a textile fabric, as shown and described.

HANS SCHWEIZER.
